tion of Delaware

Continuation of application Serial No. 417,196, March
18, 1954. This application April 25, 1957, Serial No. 10
655,004

Claims priority, application Netherlands April 17, 1953

3 Claims. (Cl. 106—165)

This application is a continuation of application Serial
No. 417,196, filed March 18, 1954, now abandoned.
The invention relates to a method for adding an adjust-
able amount of a coloring material to a viscose spin-
ning solution.

In the manufacture of spun-dyed rayon, a dyestuff
either in solution, or in a pigment suspension, is added
to the viscose spinning solution. According to the prior
art, the solution or pigment suspension is pumped into
the spinning solution feed pipe, carefully calibrated gear
pumps serving to meter the flow. Clearly, in this sort
of an arrangement, even minor variations in the pressure
in the spinning solution line will tend to produce a non-
uniformity in the mixture. Attempts have been made
to overcome the effects of small variations in the pres-
sure in the spinning solution line but the resulting appa-
ratus is exceedingly sensitive to wear, particularly
when used with titanium oxide suspensions.

Accordingly, it is an object of the present invention
to provide a method and apparatus for accurately mix-
ing an additive with a viscous spinning solution the ar-
rangement being characterized by reliability in operation
and excellent resistance to wear.

Other objects and advantages of this invention will
be apparent from the following detailed description of
an embodiment thereof in conjunction with the annexed
drawings, the single figure of which shows a schematic
layout of the system of the present invention.

Referring to the drawing in greater detail, a viscose
spinning solution is supplied through a pipeline 1 to a
spinning machine 2 via a mixer 12. The pipe 1 has a
shunt or by-pass 3 through which part of the spinning
solution flows. In this shunt there are located two gear
pumps 4 and 5 which are interconnected in series by a
tube 6. A supply pipe 7, serving to supply a dyestuff
solution or pigment suspension from a reservoir 8 dis-
charges into the tube 6. A filter 9 is inserted in the
pipe 7 and, associated with the filter, are valves 10 and
11.

During use the pipe 7 is in open connection with the
reservoir 8 for the low viscosity additive. The shunt
pipe 3 and the main viscose pipeline 1 discharges into
the mixer 12, and from the mixer 12 the mixture goes
to the spinning machine 2. The particular mixer used
at 12 forms no part of the present invention and any
known mixer may be used. The pump 4 is operated to
deliver less than the pump 5 so that a suction exists in
conduit 6 whereby the solution from conduit 7 is drawn
into the spinning solution.

Example

A viscose spinning solution was supplied under pres-
sure from a reservoir, not shown, through the pipe 1,
and in the shunt 3 the pump 4 was adjusted to deliver
144 cm.³/min., which amounted to about 1/8 part of the
amount in the main pipe 1. The tube between the pumps

2

4 and 5 had a length of 12 cm. and a diameter of 0.8
cm. The pump 5 delivered 168 cm.³/min. As a result
24 cm.³/min. of the liquid coming from the reservoir
8 was drawn into the viscose spinning solution flowing
5 through the tube between the pumps 4 and 5.

From the foregoing description it will be appreciated
that the present invention involves dividing the flow of
spinning solution into two paths and then sucking the
additive into the flow in one of those paths in such a
way that no pump in the system is required to handle
the additive alone. Because the two pumps in the viscose
line work in tandem and because both of them are han-
dling viscose solution, the wear effects of additives such
as titanium oxide suspensions are almost completely
mitigated. With the method according to the present in-
vention not only is the wear greatly reduced but the
metering of the dye solution or pigment suspension can
be maintained within a range of about 1%.

While the present disclosure involves a mixing tank 12
20 to bring about a homogeneous distribution of the addi-
tive in the entire spinning solution, attention is directed
to the fact that the gear pump 5 is itself an excellent
mixer so that the use of a mixer such as 12 is somewhat
optional. While in the illustrated embodiment the pumps
25 4 and 5 in the additive line are applied to a by-pass in
the main system, the actual proportioning of flow be-
tween the lines 1 and 3 may vary considerably even to
the point where the line 3 carries more than half of
the total spinning solution.

While most of the work in connection with this in-
vention has been done with aqueous solutions and sus-
pensions, the method is generally applicable to the in-
troduction of low viscosity liquids for admixture with
35 high viscosity liquids.

What is claimed is:

1. A process for dispersing a coloring material uni-
formly throughout a viscose spinning solution which com-
prises supplying a viscose solution to an input zone,
40 dividing the flow of solution and passing the major por-
tion directly to a principal mixing zone, by-passing the
minor portion and propelling the same to a color sus-
pension adit zone while supplying a constant amount
45 of a color suspension to said adit zone wherein the minor
portion is premixed with the suspension in substantially
the same concentration, positively withdrawing the mix-
ture from the adit zone at a higher rate than the minor
50 portion is propelled thereto prior to entry in the adit
zone to induce flow of the suspension and finally passing
the mixture to said principal mixing zone into which the
major portion is being discharged.

2. A process for dispersing a coloring material uni-
formly throughout a viscose spinning solution which com-
prises supplying a viscose solution to an input zone,
55 dividing the flow of solution and passing the major por-
tion directly to a principal mixing zone, by-passing the
minor portion and propelling the same to a color sus-
pension adit zone while supplying a constant amount of
60 a color suspension to said adit zone wherein the minor
portion is premixed with the suspension in substantially
the same concentration, inducing flow of the suspension
to the premixing zone solely by positively withdrawing
the mixture from the adit zone at a higher rate than the
65 minor portion of spinning solution is supplied thereto,
and finally passing the mixture to said principal mixing
zone into which the major portion is being discharged.

3. A method for adding a predetermined proportion
70 of a pigment dispersion automatically and continuously
to a stream of viscose spinning solution comprising pass-
ing the main stream of viscose into a blending zone be-
fore it enters the spinnerets, diverting a minor portion of
the viscose stream through a shunt line having a pair

of tandem pumps which discharge into said blending zone, and introducing a stream of additive into the shunt line at a point between the two pumps, the pump preceding this point having a smaller capacity than the other pump so that the amount of additive is equal to the 5 difference in capacity between the two pumps.
